(No Model.)

J. KNITTEL.

DRUM.

No. 478,611.

Patented July 12, 1892.

Fig. 1

UNITED STATES PATENT OFFICE.

JOHN KNITTEL, OF ST. LOUIS, MISSOURI, ASSIGNOR OF ONE-HALF TO GEORGE T. KOLLAS, OF SAME PLACE.

DRUM.

SPECIFICATION forming part of Letters Patent No. 478,611, dated July 12, 1892.

Application filed December 8, 1891. Serial No. 414,354. (No model.)

To all whom it may concern:

Be it known that I, JOHN KNITTEL, of the city of St. Louis and State of Missouri, have invented certain new and useful Improvements in Drums or Drum-Heads for Musical Instruments, of which the following is a full, clear, and exact description, reference being had to the accompanying drawings, forming a part hereof.

10 My invention relates to improvements in drums or drum-heads for musical instruments; and it consists in the novel arrangement and combination of parts, as will be more fully hereinafter described, and designated in the 15 claims.

In the drawings, Figure 1 is a vertical section of a drum constructed according to my invention. Fig. 2 is a cross-section taken on the line $x-x$ of Fig. 1. Fig. 3 is a side elevation, partially broken away, showing the exterior surface of the drum. Fig. 4 is a side elevation of the tool which I employ in connection with the drum. Fig. 5 is an enlarged detail view of the adjusting device for the 25 snares, and Fig. 6 is a detail view of a modification of my invention.

The object of my invention is to effectually and evenly tighten the heads of the drum or other instruments having a hide stretched 30 thereon, and, further, to dispense with the ordinary strings which form the snare on the bottom of the drum and in place thereof form a snare of such construction which is entirely located within the drum, and which can be 35 accurately adjusted from the outside of said drum.

With these objects in view, I shall proceed to describe the construction in detail, and the manner in which the same is carried out.

40 The drum that I am about to describe is constructed entirely of metal, and will present a neat and finished appearance.

Referring to the drawings, 1 represents the body of the drum, the upper and lower edges of 45 which are similarly constructed, and therefore I shall only describe one in detail—namely, the upper part of said drum. Adjacent to said upper edge, and at a suitable distance therefrom, are formed external screw-threads 50 2, which may be of any suitable number in order to accomplish the desired result. In

order to be more explicit as to the construction of this portion of the drum, an annular flange 3 is formed entirely around the body 1 of the drum, upon the circumference of which 55 said screw-threads are formed, by means of which a suitable space is left from said annular flange to the upper edge of the body 1, for the purpose as hereinafter more fully set forth.

4 represents a rim which is a little larger 60 than the upper edge of the drum 1, and having formed upon its inner circumference internal screw-threads 5, which are adapted to receive the screw-threads 2 when the said rim is adapted to be secured to the body of the 65 drum for uniting the parts, as hereinafter more fully set forth. The upper edge of the rim 4 is rounded in cross-section, and has an internally-formed flange 6, the under surface of which flange is provided with an annular 70 groove 7.

8 represents a metallic ring, which is of such a size and dimension as to fit snugly within the annular groove 7 of the rim, as shown in Fig. 1, which when so placed in said 75 rim presents a smooth surface for the head of the drum.

9 represents a metallic ring similarly constructed—namely, in size and dimensions—as the ring 8, over which the head 10 of the 80 drum is placed and stretched before the same is inserted or placed in its proper position in the rim 4. When the ring 9 is covered with the rawhide or, more properly, the drum-head, as above stated, the ring, together with the 85 head, is placed upon the ring 8 in the rim 4 and while in this position the parts are united, as shown in Fig. 1.

The upper edge 11 of the body of the drum is of such a size in circumference as to bear 90 upon the inner surface of the ring 8, and thereby come in contact with the hide to form the head of the drum and firmly clamp the said hide to the ring 8. If this were not true, the said head would have a tendency to withdraw from the said ring 8 when the head of the drum was stretched to the desired tension.

When the parts have been united, as above described, and the internal threads formed on 100 the rim 4 in position to receive the external screw-threads formed on the flange 3 by turn-

ing the said rim in the proper direction or to the right, the ring 8, carried by said rim, will be brought in contact with the upper surface of the head 1, and by further turning the said rim in the same direction the proper tension to the head is obtained.

It will be readily perceived that it would be impossible to give the desired tension to the head of the drum without some additional contrivance or tool constructed for the purpose. This I accomplish by means of a tool 12, constructed and applied in a manner as hereinafter described. 13 represents a series of holes formed in the rim 4, within which holes the said tool is easily inserted.

The tool 12 is composed of a handle 14, by means of which the same is manipulated, and having lateral extensions 15, the base of which conforms to the shape of the rim 4 and is adapted to come in contact therewith. To said base portion is secured a hook 16, which hook is adapted to be inserted into the openings 13, formed in the rim. When the tool 12 is applied in the proper manner, the hook will pass into said openings or in whatever opening it is desired to be inserted and by a slight pressure upon the handle of said tool in either direction the rim 4 may be turned and the desired tension given to the drum-head.

30 In Fig. 6 of the drawings I have shown a modification in which the tool employed to tighten the drum is dispensed with, and consequently the openings formed in the rim 4 are also dispensed with. In this instance I effect the desired tension in a manner as herein-after described.

17 represents fine gear-teeth formed upon the outer circumference of the rim 4, which teeth are adapted to mesh with a suitable 40 worm carried by the body of the drum.

18 represents the worm, which is mounted in suitable bearings 19, carried by the body of the drum 1. Said worm is provided with an extension 19', by means of which the said 45 worm is turned, in order to accomplish the desired result.

From the foregoing description it will be seen that when the worm 18 is turned the rim 4 will also be turned, causing the head of the 50 drum to be effectually stretched.

To the inner cylindrical surface of the body of the drum 1, at any suitable location, is secured a block 20, having a series of vertical apertures 21 formed therein.

55 22 represents a series of steel wires corresponding to the number of openings formed in the block 20, one end of said wires being suitably bent at an angle and said ends passed into the openings 21 in the block 20. The opposite ends of said wires are provided with balls 23, which are adapted to come in contact with or be adjusted to and from one of the heads of the drums. From the block 20 the said wires converge, as best shown in Fig. 65 2 of the drawings, in order that the lower ends of said wires will come in contact with

the drum-head properly in order to effect the result.

24 represents a screw-threaded opening formed in the side of the body of the drum, 70 through which a screw-threaded bolt 25 is adapted to be turned for adjusting the wires simultaneously. To one end of the screw is secured a knob 26, by means of which the same is manipulated or turned, and formed on the 75 opposite end of said bolt is an annular depression 27.

28 represents a washer, which is adapted to snugly fit in said recess 27, and formed with said washer at the edge thereof are two perforated ears 29, which are oppositely located.

30 represents a curvilinear bar or plate which rests upon the upper surface of the wires 22, and to the ends of said curvilinear plate are secured two wires 31, leading to and 85 connected to the ears 29, forming a part of the washer 28. It will be premised in this connection that the wires employed being constructed of steel will always have a tendency to raise the lower end thereof from the 90 head of the drum. When the screw 24 is turned to the right, the curvilinear plate 30 will be pressed upon the wires and cause the ends of the same to be brought in contact with the head of the drum; but when said 95 screw is turned in the opposite direction the said curvilinear plate 30 will allow the wires or the lower ends thereof to rise from the head of the said drum.

By the use of the snare, as described, the 100 ordinary strings generally employed for the purpose are entirely dispensed with and the result obtained in a more efficient manner.

My invention is equally applicable to banjos or to any other instruments having a head, 105 and therefore I do not wish to limit myself to any one application.

Having fully described my invention, what I claim is—

1. A drum or drum-head for musical instruments having external screw-threads formed on the body of the instrument and a rim having internal screw-threads formed upon the same for receiving the said external threads, substantially as set forth. 115

2. A drum or drum-head for musical instruments, consisting of a body, external screw-threads formed on the same, a rim provided with internal screw-threads for receiving the screw-threads formed upon the said 120 body, and a head adapted to be clamped between said rim and body, substantially as set forth.

3. A drum or drum-head for musical instruments, consisting of a body, external 125 screw-threads formed upon the same, a rim having internal screw-threads adapted to receive the said external screw-threads, a head adapted to be clamped by said rim, and means for turning said rim, substantially as set 130 forth.

4. A drum or drum-head for musical in-

struments, consisting of a body 1, having an annular flange formed thereon, external screw-threads formed on the said flange, a rim, such as 4, provided with internal screw-threads 5 adapted to receive the said external threads, an annular flange internally arranged upon said rim, a groove formed in the said flange for receiving a ring, a head, such as 10, adapted to be stretched over a ring 9, and the same 10 interposed between the first-named ring and the upper edge of the body 1, substantially as set forth.

5. A drum or drum-head for musical instruments, consisting of a body, external screw-threads formed upon the same, a rim 15 having internal screw-threads adapted to receive said external threads, holes formed in

the said rim, within which a suitable tool is adapted to be inserted, and a head adapted to be interposed between said rim and body, 20 substantially as set forth.

6. A snare for drums, consisting of a series of spring-wires rigidly secured at one end within the drum, a plate overlying said wires, an adjustable screw carried by the drum, a 25 washer loosely mounted thereon, and wires connecting said plate and washer, substantially as set forth.

In testimony whereof I affix my signature in presence of two witnesses.

JOHN KNITTEL.
